UNITED STATES PATENT OFFICE.

SARAH E. BEMIS, OF PHILADELPHIA, PENNSYLVANIA.

CORSET.

Application filed June 28, 1922. Serial No. 571,374.

To all whom it may concern:

Be it known that I, SARAH E. BEMIS, a citizen of the United States, residing at Philadelphia, in the county of Philadelphia and State of Pennsylvania, have invented 5 certain new and useful Improvements in Corsets, of which the following is a full, clear, and exact description.

My invention relates to corsets, and has 10 for its object to provide means whereby ladies may carry valuables about their person with perfect safety. To this end, I have provided the corset with one or more pockets on its inner side; the pockets being of such 15 size and shape as to carry passports, money and other valuables.

Another object of the invention is to attach the pocket to the corset in such manner that the latter will not be disfigured by rows 20 of stitching or the like.

Other objects and advantages of the invention will be apparent from the following description when taken in connection with the accompanying drawing, in which:

25 Figure 1 is a perspective view of the corset in use.

Figure 2 is an elevation of the corset per se, the pocket flap being shown in open position.

30 Figure 3 is a vertical section through the pocket taken on line 3—3 of Figure 2, looking in the direction of the arrow.

Referring to the drawing more in detail, the numeral 1 designates a corset of the 35 type which extends from the waist line downwardly, although the invention may be applied to other types as well. Each half of the corset is composed of three panels 2, 3 and 4, the panels being defined by the 40 stiffening strips or ribs 5 seamed along the edges of the panels.

In the form of the invention shown in Figures 1, 2 and 3, each of the central panels 3 is extended below the body of the corset 45 and folded inwardly upon itself to form a wall 6 of the pocket, the other wall of the pocket being formed by a portion of the panel 3. Each side edge of the turned over portion 6 is placed under the rib seam and 50 stitched thereto, as indicated in Figure 2,

thereby forming the pocket without disfiguring the corset. A flap 7 is stitched to the panel 3 and is provided with a fastening means 8 to co-operate with a complementary fastening means 9 on the wall of the pocket. 55

As the pocket is located on the interior of the corset and is exposed to moisture due to perspiration, which is liable to damage the contents of the pocket, it has been found advisable to employ a waterproof lining, as 60 indicated at 10. This lining 10 may be of rubber, rubberized fabric or similar waterproof material.

From the foregoing description it will be seen that I have combined with a corset one 65 or more moisture-proof pockets which are concealed on the interior thereof and provide an extremely safe means for carrying money or other valuables. Furthermore, it should be noted that the exterior of the 70 corset is in nowise marred or disfigured by the attachment of the pocket thereto.

In accordance with the patent statutes, I have described what I now believe to be the best embodiment of the invention, but 75 I do not wish to be understood thereby as limiting myself or the scope of the invention, as many changes and modifications may be made without departing from the spirit of the invention; all such I aim to include 80 in the scope of the appended claims.

What I claim as new and desire to secure by Letters Patent is:

1. A corset composed of panels of flexible material, stiffening ribs seamed along the 85 edges of the panels, one of said panels being extended below the body of the corset and folded upon itself to form a pocket, the side edges of the folded portion being stitched by the seams which hold the stiffening ribs. 90

2. A corset composed of panels of flexible material, stiffening ribs seamed along the edges of the panels, one of said panels being extended below the body of the corset and folded inwardly upon itself to form a pocket 95 on the inner wall of the corset, the side edges of the folded portion being stitched by the seams which hold the stiffening ribs, and a waterproof lining for said pocket.

SARAH E. BEMIS (MRS. E. E.).
